[57] CLAIM

The ornamental design for a carburetor inspection and repair stand, as shown and described.

DESCRIPTION

FIG. 1 is a top plan view of a carburetor inspection and repair stand, showing my new design;

FIG. 2 is a front elevational view, the rear being a mirror image thereof;

FIG. 3 is a right side elevational view, the left side being a mirror image thereof; and

FIG. 4 is a bottom plan view thereof.

FIG. 1

FIG. 2

FIG. 3

FIG. 4
